UNITED STATES PATENT OFFICE.

WILLIAM H. PRIESS, OF BELMONT, MASSACHUSETTS, ASSIGNOR TO WIRELESS SPECIALTY APPARATUS COMPANY, OF BOSTON, MASSACHUSETTS, A CORPORATION OF NEW YORK.

ELECTRICAL CONDENSER AND METHOD OF MAKING THE SAME.

Application filed December 5, 1921. Serial No. 519,867.

This invention relates to electrical condensers and methods of making the same. In particular, the invention is applicable to small mica condensers for use as magneto condensers or in ignition systems or for other purposes.

An object of the invention is a condenser of simple but effective construction which can be manufactured at low cost, all as more particularly pointed out hereinafter.

The invention consists of the condenser structure including the arrangement of parts hereinafter disclosed.

In the accompanying drawings, I have illustrated one embodiment of my invention in which

Figure 1 is a plan view, on an enlarged scale, of the assembled condenser;

Fig. 2 is an elevation of the same;

Fig. 3 is a sectional elevation thereof on the line 3—3 of Fig. 1, on an enlarged scale, the stack being illustrated in elevation;

Fig. 4 is a detail perspective view of one of the clamping plates;

Fig. 5 is a detail perspective view of an insulating sheath for the condenser;

Fig. 6 is a detail perspective view of one of the condenser foil armatures;

Fig. 7 is a detail perspective view of a clip plate;

Fig. 8 is a detail perspective view of a clip;

Fig. 9 is an elevation of a mica sheet used in building the stack; and

Fig. 10 is an elevation of the other clamping plate, the first being shown in Fig. 4.

In the construction of the condenser of the present invention, the stack S is built up of alternate sheets of foil 1 (Fig. 6) and square sheets of dielectric such as mica 1^a (Fig. 9) having rounded corners. As clearly shown in Fig. 6, the foil sheets 1, of simple contour, are provided with tabs 3, 4, which are so arranged during the building of the stack as to project alternately at spaced points as at opposite sides of the stack as illustrated in Figs. 1 and 2 at 3, 4. Preferably the mica sheets, before the stack is built, are varnished. This varnishing may be done by the method described in my pending application 377,977, filed April 30, 1920. After the required number of foil

sheets and dielectrics have been assembled into a stack, the stack is baked and then 55 tested for voltage and capacity as described in my co-pending application above mentioned. It is to be understood, however, that any suitable method of assembling and treating the stack may be employed. 60

After the condenser stack of the simple square contour above described has been finished, the projecting foil tabs constituting terminals 3 and 4 are cut off or clipped by any suitable means such as an electrical- 65 heated strip. The foil ends or terminals 3 and 4 respectively are then dipped into a low melting point alloy having a melting point lower than the melting point of the foil employed in the condenser, whereby the 70 foils of like polarity in the respective groups 3 and 4 of opposite polarity are positively connected together in good electrical contact. This alloy preferably consists of two parts 75 tin and one part bismuth, which is maintained at a temperature of approximately 180° to 190° C., the melting point of the foil employed being around 230° C. The alloy has a melting point of approximately 150° to 160° C. Hence, there is no tendency to 80 melt off the tin foil of the projecting tabs 3, 4 in soldering, and a good soldered joint is secured, providing a condenser in which there are no floating foils, and in which the electrical connection between foils of like 85 polarity is not dependent upon the pressure on the stack.

The stack S is now assembled in its clamp C, which comprises a stiff metal clamp plate 5 (Fig. 10) engaging one end face of stack 90 S. This plate 5 is preferably of brass and is provided at its opposite ends with apertured ears 5^a.

The type of condenser disclosed herein by way of example is designed as to shape, 95 etc., to fit into standard ignition systems casings (not illustrated) and is designed to be electrically connected to the breaker box and casing as well as the coil of such ignition systems, all of which, being of well-known 100 design, need not be illustrated. For this purpose, the clamping plate 5 is provided with a projecting stud 6 adapted to fit into an insulated bore of the ignition casing or box- 105 ing, this stud, when the condenser is assembled in the ignition casing, being electrical-

ly connected to the breaker box by means of a screw adapted to be threaded into the threaded bore in stud 6 as illustrated in Fig. 2. Interposed between the stack S and the plate 5, however, is a sheet 7 of insulation, (Figs. 2 and 3), preferably of fish paper.

Upon the opposite end face of the stack is placed a square sheet of mica 8 (Fig. 3) of the general size and shape of the dielectric sheets of mica 1^a (Fig. 9) constituting the condenser stack, although preferably slightly thicker, and upon this sheet 8 rests a metal terminal or clip plate 9 illustrated in Fig. 7 and adapted to be stamped out from sheet metal. Clip plate 9 is provided at one side with an apertured tongue or lug 10 whereby the condenser and its assembled clamp may be secured within and to the casing of the ignition device by any desired securing means. At an opposite portion of the plate 9 is a depending tab 11, adapted to be electrically connected to the terminal 3 of the condenser stack as illustrated in Figs. 1 and 2. Connected to plate 9 in spaced relation to the tab 11 is an integral clip 12 projecting beyond the stack S and having tabs 13 thereon adapted to be bent over a wire lead (not illustrated) connected to the ignition coil, which lead may be soldered to the clip 12, if so desired. Stamped sheet metal terminal plate 9 constitutes a stiff member the main body of which lies in the stack and an integral portion of which, as 10, extends outside the stack as a stiff portion adapted for attachment thereto of a circuit lead without injuring the terminal plate itself or its integral projection; and such stiff projecting portion is advantageous in resisting bending which might result in short circuiting or in damaging the insulation, and in permitting mechanical mounting of the condenser. On top of the clip plate 9 is located a second sheet 14 (Fig. 3) of insulating material, such as mica, and located upon the sheet 14 is the opposite metal clamping plate 15 separately shown in Fig. 4 as comprising at opposite sides thereof apertured ears 15^a adapted for co-operation with the apertured ears 5^a of bottom clamp plate 5 of Fig. 10. Plate 15 is a spring plate which, when not under compression, is curved as illustrated in Fig. 4. Metal rivets or other securing means 16 extend through the apertured ears 15^a and 5^a (of clamp plates 15 and 5 respectively), and are spun over to secure the plates 5 and 15 together in clamping relation against the stacks. Plate 15, as well as the entire clamp C, Fig. 3, including plate 5 and rivets 16, is thoroughly insulated from the clip plate 9 and, upon the securement of the rivets, the plate 15 is flattened out as illustrated in Fig. 2, whereby uniform spring pressure is exerted over the active area of the stack while the

condenser is in service. Plate 15 may comprise any suitable springy material such as phosphor bronze.

The rivets or other securing means 16 are spaced a substantial distance from the sides of stack and from the sheets of foil and dielectric constituting the stack and from terminal plate 9, and are entirely independent thereof. The rivets connecting plates 5 and 15 are spun over to secure the plates together as indicated at 17 (Fig. 2). A single pair of oppositely-arranged rivets is sufficient to hold the stack under uniform compression by means of the clamp C, Fig. 3 and to flatten out spring plate 15. The foil terminal 3, constituting the common terminal of the foils of one polarity, is connected by a lead 18 (Fig. 2) to the depending tongue 11 of clip or terminal plate 9 of Fig. 7, while the other terminal 4 of the condenser (Fig. 2) is electrically connected to the clamp C as through one of the rivets 16 by a copper lead 19, soldered to the rivet as illustrated in Figs. 1 and 2. The clamp C, including the clamping plates 5 and 15 and rivets 16, constitutes the high potential terminal of the condenser, while the plate 9, insulated from the clamp by sheets 8 and 14, constitutes the low potential terminal.

As above mentioned, the low potential end of the stacks is connected by the clip 12 (Fig. 7) to the ignition coil, while the high potential end of the stack is likewise connected to this coil when the condenser is assembled in the ignition system device, by means of a metal clip 20, Fig. 8, mounted upon plate 15 and secured thereto by one of the rivets 16, the clip 20 having an opening through which the rivet passes. This clip 20 is provided with tabs 21, to which the lead from the ignition coil may be secured or soldered. The clip is held against dislocation or movement around the rivet as an axis by means of a pair of prongs 22 thereon, which when the condenser is assembled are bent around the edges of an adjacent ear 15^a of the plate 15 (Fig. 4) as illustrated in Figs. 1 and 2.

When the condenser has been assembled as above described, an insulating sheath 23 (Fig. 5), preferably of fish paper, is placed around the condenser and its clamp as illustrated in Figs. 1-3. This member 23 is provided with a central hole 24 through which the stud 6 (Figs. 2-3) is adapted to extend. Sheet 23 also is provided with lateral stack-casing portions 25.

After the member 23 has been placed around the condenser, the condenser is placed within the ignition system box or casing, and the tab 10 of clip or terminal plate 9 of Fig. 7 is secured to the same, as a circuit terminal extending between clamp plates 5 and 15 beyond the side of stacks and electrically connecting the low potential terminal of the condenser to the casing of the ignition device.

The stud 6, which is insulated from such casing, is then electrically connected to the breaker box, whereby the high potential end of the condenser is electrically connected to 5 the breaker box. The leads from the ignition coil are then connected or soldered to the clips 12 and 20.

The condenser of this invention is much cheaper than the ignition condensers now in 10 use, for the reason that assembling costs have been reduced on account of the simple symmetrical contour of the sheets of foil and dielectric. Furthermore, the amount of mica necessary for a given capacity is less, materially reducing the area and thickness of the 15 stack, making a more compact and smaller condenser as well as reducing the cost. The number of rivets is reduced to a minimum, two or more located at opposite sides of the 20 stack in spaced relation thereto being ample to secure plates 3 and 15 together with sufficient pressure upon the stack to maintain the sheets in intimate contact, the spring plate 15 providing means to allow expansion 25 of the stack under heating conditions. In the condenser of the present invention, there are no floating plates, the foil sheets of like polarity having good electrical contact with each other and with the clip plate 9 or with 30 the condenser clamp C itself. The metal parts of the condenser may be easily stamped out from sheet metal, and then manufacture and assembly may be done very easily and at low cost. Inasmuch as the rivets are independent of the mica, the highest degree of 35 pressure may be obtained without danger of splitting the mica, this pressure maintaining the sheets of foil and dielectric in intimate contact.

40 It is to be understood that the invention is not limited to the embodiments and features specifically shown and described herein, but that such embodiments and features are subject to changes and modifications 45 without any departure from the spirit of the invention.

I claim:—

1. An electrical condenser which comprises a stack of sheets of metal foil and mica and 50 a metal clip-plate at one end of the stack and having insulating sheets on both its faces; the foils having parts extending beyond the micas and clip-plate; metal clamping plates on opposite ends of the stack, one of which 55 lies against the insulating sheet outside the clip-plate, and both of which are connected together in clamping relation with the stack at points external to the stack of sheets and clip-plate; means electrically connecting together the foil extensions of like polarity; 60 said clip-plate being formed with a depending tongue; and a lead connection between one set of foil connections and said tongue.

2. In an electrical condenser, the combination with a stack of condenser sheets of

metal foils and dielectrics, of at least three metal plates stacked together with said condenser sheets and extending over substantially the entire active areas of the condenser sheets in the stack; two of said metal plates 70 lying as clamping members on the end faces of the stack and holding the condenser sheets tightly together throughout their active areas; and said third plate constituting a condenser terminal by being connected to the 75 stack foils of one polarity and insulated from the end clamping plates but lying between them and thereby subjected to their compression and held from lateral displacement; and securing means extending from a clamp- 80 ing plate at one end of the stack to the clamping plate at the other end, said securing means holding the two clamping plates in their compressing relation with the stack sheets and said condenser terminal plate. 85

3. An electrical condenser which comprises a stack of sheets of metal foils and mica, the foils having parts projecting beyond the micas at opposite parts of the stack and constituting foil-terminals of opposite polarity; 90 metal soldering together the foil-sheets of the foil terminals outside the stack and having a lower melting point than the foil-sheets; two metal clamping plates on the respective stack-ends and projecting beyond the mica 95 sheets from the same sides of the stack as the foil-terminals but extending beyond the latter; rivets located outside the stack and connecting together the clamping-plate extensions; and a metal lead electrically connecting one set of foil-terminal-extensions so soldered with the adjacent rivet of the clamping plates.

4. In an electrical condenser, a stack having terminals, a clamp for said stack comprising a pair of plates arranged upon opposite ends of the stack, means for mechanically connecting said plates, a clip plate associated with said stack and said clamp and insulated therefrom, said clamping plates 100 and clip-plate extending over substantially the entire active areas of the condenser sheets, and means electrically connecting one terminal of the stack to said clip plate and electrically connecting said clamp to the 105 other terminal of said stack.

5. In an electrical condenser, a stack comprising alternate sheets of foil and dielectric and having terminals, a clip plate mounted at one end of the stack and insulated therefrom, clamping plates enclosing said stack and clip plate and insulated therefrom, rivets arranged upon opposite sides of the stack and spaced therefrom and connecting said clamping plates, means electrically 120 connecting one terminal of the condenser to said clip plate, means electrically connecting the opposite terminal of said condenser to the clamp, and a clip secured to said clamp. 125

6. In an electrical condenser, a stack com-

prising alternate sheets of foil and dielectric; a clip plate comprising a depending tongue, a clip member and securing member mounted with said stack and insulated therefrom, clamping plates enclosing said stack and clip plate, insulated therefrom and provided with projecting ears extending beyond the stack, rivets extending through said projecting ears and connecting said clamping plates, means electrically connecting the foil of one polarity to said depending tongue, means electrically connecting the opposite foil of said condenser stack to said clamp, and a clip on one of said rivets and provided with prongs engaging opposite edges of an ear of one of said clamping plates, whereby it is secured against movement.

7. In an electrical condenser, a stack of symmetrical sheets of dielectric and sheets of foil having tabs projecting alternately, clamping plates upon opposite sides of the stack and connected together in clamping relation to the stack at points external of the stack, a plate interposed between said stack and clamp and insulated from said clamp, said clamping plates and interposed plate extending over substantially the entire active areas of the condenser sheets and means electrically connecting said alternate tabs to said clamp and intermediate plate respectively.

8. In an electrical condenser, a stack of alternate sheets of foil and dielectric, clamping plates on opposite end faces of said stack, rivets connecting said plates, and a separable clip mounted on one of said rivets and having prongs engaging a clamping plate to prevent the movement thereof on the rivet.

9. In an electrical condenser the combination with a stack of condenser sheets of metal foils and dielectrics, of at least three metal plates stacked together with said condenser sheets and extending over substantially the entire active areas of the condenser sheets in the stack; two of said metal plates lying on the end faces of the stack as clamping plates therefor whereby the condenser sheets are held tightly together substantially throughout their active areas, and at least one of said clamping plates being springy and inherently curved; and said third plate constituting a condenser terminal by being connected to the stack foils of one polarity and insulated from said end clamping plates but lying between them and thereby subjected to the compression thereof and held from lateral displacement; and securing means extending from a clamping plate at one end of the stack to the clamping plate at the other end and holding the clamping plates in their compressing relation with the condenser sheets and condenser terminal plate.

10. An electrical condenser comprising a stack of dielectric sheets and metal foil armatures; a stiff sheet metal terminal plate located against and covering the end face of the stack and conductively connected to the stack foils of one polarity thereby constituting said plate a terminal of the stack; a pair of sheet metal clamping plates located against and covering the end faces of the stack; and extending over substantially the entire active areas of the condenser sheets; sheet insulation between said terminal plate and the adjacent clamping plate; sheet insulation between the other end of the stack and the other clamping plate; and securing means holding the clamping plates in clamping relation to the stack and terminal plate; said terminal plate having an integral stiff circuit terminal portion extending from and beyond a side of the stack and between said clamping plates.

11. An electrical condenser comprising a stack of dielectric sheets and metal foil armatures; a stiff sheet metal plate located against an end face of the stack and constituting a terminal thereof; metal clamping means acting on the ends of the stack and clamping the stack and said terminal plate between them; and extending over substantially the entire active areas of the condenser sheets; and said terminal plate being insulated from said clamping means and having an integral stiff circuit terminal portion extending from and beyond a side of the stack and between the clamping means on the stack ends.

12. An electrical condenser comprising a stack of dielectric sheets and metal foil armatures; a stiff sheet metal plate located against an end face of the stack and constituting a terminal of the stack; a pair of sheet metal clamping plates located against the opposite end faces of the stack; and extending over substantially the entire active areas of the condenser sheets; said terminal plate being insulated from said clamping plates; and riveting means holding the clamping plates in clamping relation to the stack and said terminal plate; said terminal plate having an integral stiff circuit terminal portion extending from and beyond a side of the stack and between said clamping plates.

13. An electrical condenser comprising a stack of dielectric sheets and metal foil armatures; a stiff sheet metal plate located against an end face of the stack and conductively connected to the stack foils of one polarity thereby constituting said plate a terminal of the stack; metal clamping means acting on the ends of the stack and clamping the stack and said terminal plate, said clamping means being insulated from said terminal plate and conductively connected to the stack foils of opposite polarity there-

by constituting said clamping means as another terminal of the stack; and extending over substantially the entire active areas of the condenser sheets; said terminal plate 5 having an integral stiff circuit terminal portion extending from and beyond a side of the stack and between the clamping means on the stack ends.

14. An electrical condenser comprising a 10 stack of dielectric sheets and metal foil armatures; a stiff sheet metal terminal plate located against an end face of the stack and constituting a terminal of the stack; metal

clamping means acting on the ends of the stack and clamping the stack and said terminal plate, said clamping means being insulated from said terminal plate and constituting another terminal of the stack; and extending over substantially the entire active areas of the condenser sheets; said terminal 15 plate having an integral stiff circuit terminal portion extending from and beyond a side of the stack and between the clamping means on the stack ends. 20
